WELDED BOAT CONSTRUCTION

John F. Mercer, Washington, D. C.

Application September 9, 1943, Serial No. 501,702

7 Claims.

(Cl. 114—79)

This invention relates to an improved method and means of constructing a boat out of welded sheet metal.

An object of this invention is to provide an improved boat construction of sheet metal welded together, wherein any tendency of the metal to buckle during the welding operation will be eliminated.

Another object of this invention is to provide in a small boat construction an improved rib and hull plating or shell which will permit prefabrication of the parts.

Another object of this invention is to provide in a small boat construction an improved rib and hull plating or shell wherein any slight errors in construction can be easily corrected during the welding of the parts.

Another object of this invention is to provide in a small boat construction, in combination, a rib or frame element and a metal plank which is adapted to interlock with the rib, the plank being formed with a lower inwardly projecting flange which provides for reinforcing the thin metal and will simulate the lapped board construction.

A further object of this invention is to provide in a small boat construction an improved metal plating or planking which is formed with a flat outer side and a flanged lower edge, the flange of the lower edge of a succeeding plating contacting with the flat outer side of the upper portion of a preceding plating, the flange providing a bendable part, and the angle formed by the flange may be varied under expansion or contraction during the welding operation to correct minor errors in construction or assembly so that close tolerances between the parts may be eliminated.

To the foregoing objects and others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing:

Figure 1 is a fragmentary transverse vertical section of a small boat constructed according to an embodiment of this invention.

Figure 2 is a fragmentary side elevation looking from the inside.

Figure 3 is a fragmentary perspective view of one of the metal planking or plating members, and

Figure 4 is a view similar to Figure 3 showing a modified form of this construction.

Referring to the drawing, the numeral 10 designates generally a rib or frame member which is bent longitudinally to the desired shape, being

formed of a flat strip of metal. The rib or frame member 10 is formed with a plurality of stepped outer portions 11 providing lower shoulders 13 and the rib 10 at the junction of the shoulder 13 with the flat outer portion 11 is provided with an upwardly projecting slot 12.

A sheet metal plating or planking generally designated as 14 is adapted to be secured to the stepped portions 11 and the shoulders 13 and 10 comprises a substantially flat body 15 which has the opposite longitudinal edges thereof shaped to provide the desired configuration of the hull, and the body 15 at its lower edge is formed with an inwardly projecting flange 16. The flange 16 is 15 adapted to engage against the shoulders 13 of the various ribs whereas the upper edge of the body 15 is adapted to be extended upwardly into the slot 12, as shown in Figure 1.

Initially the inner side of the body 15 is tacked 20 adjacent the lower part thereof to the ribs 10 and the flange 16 of a succeeding plating or planking is adapted to abut at its inner free edge against the outer side of a preceding planking or plating at a point slightly below the upper edge of the preceding planking or plating. The flange 16 is 25 then be initially tacked by welding to the outer side of a preceding body 15, whereupon the flange 16 may be welded, as at 17, to the body 15 of a preceding planking.

The inner side of the body 15 and of the flange 16 may then be welded, as at 18, to the various 30 ribs, the welding 18 being disposed on opposite sides of the rib 10, as shown in Figure 2. If desired the notches 12 above the upper edges of the body 15 may then be filled in by welding, as at 35 19, so that a solid metal body construction will be provided for the boat.

The flange 16 is here shown as disposed at substantially right angles to the body 15, and 40 it will be understood that this angle may be greater or less to a small degree in order to correct any inaccuracies in the cutting of the metal, and the expansion or contraction of the metal during the welding operations. The provision of 45 the flange 16 will provide a hull construction simulating lapped planking and the flange 16 will provide a reinforcing element to hold the body 15 against bending or buckling in addition to providing a means for readily correcting any 50 slight errors in fabricating of the planking elements.

It is contemplated that the boat to be constructed according to this invention is a relatively small boat and that the sheet metal forming the planking 14 will be made out of fairly light gauge material.

In Figure 4 there is disclosed a modified form 55 of this construction, wherein the rib or frame member 10a has secured thereto a shell forming plating or planking 20 which includes a pair of

integral plating or planking members 14a and 14b. In the present instance, the lower edge of the plating or planking member 14a is formed with a right angle flange 16a integral with the upper edge of the body 15b of the lower member 14b, and the rib or frame member 10a is provided with a shoulder 13a wherein the notch for receiving the upper edge of the preceding member 14b is eliminated.

The upper edge of the plating or planking member 14a is adapted to engage in a notch 12a formed in the rib or frame member 10a, and the lower flange 16b is adapted to engage against the shoulder 13b of a step 11b which is formed on the outer edge of the rib 10a. The inner side of the plating member 20 is adapted to be welded as at 18a to the opposite sides of the frame or rib 10a, and the lower flange 16b is adapted to be welded as at 17a to the upper edge portion and the outer side of a preceding plating or planking member.

With a construction as disclosed in Figure 4, the width of the plating members may be varied as desired to simulate either narrow or wide planking and by providing a plurality of these plating members which are integral with each other a considerable amount of welding may be eliminated.

A vessel or boat constructed according to this invention will be reinforced against denting or buckling due to the flanges at the lower edges of the plating or planking members, and in the event there is any noticeable expansion or contraction of these members during the assembly operation, the various plating members can be readily secured together, due to the compensating feature herein provided, wherein the lower flange of a succeeding plating member overlaps the upper portion of a preceding plating member. The ribs 10 and 10a may be of either flat construction disposed with their narrow edge outermost or may be of T-shape construction in transverse section.

The method hereinbefore described of forming the hull of a small boat will provide for the easy and quick assembling of the shell which operation may be formed by any welder, the welding operation of the outer side of the hull being capable of being performed by turning the hull upside down and then welding the plating to the ribs and the various plating members to each other.

What I claim is:

1. A welded sheet metal boat comprising ribs formed with stepped outer edge portions and an upwardly projecting notch between certain of said stepped portions, plating members engaging on said stepped portions, the upper edge of each plating members engaging in said notch, said members including a relatively flat body and an inwardly projecting lower flange, the lower flange of a succeeding plating member overlapping the upper portion of a preceding plating member, and welding securing the flange of a succeeding

member to the upper portion of a preceding member and also securing said members to said ribs.

2. A welded sheet metal boat as set forth in claim 1 wherein each flange is disposed in abutting relation to the shoulder formed between the stepped portions of said ribs.

3. A welded sheet metal boat comprising ribs formed with outer stepped edges and an upwardly extending notch between each step, a plurality of plating members, each member being formed of a body part and a lower inwardly projecting flange, the upper edge of said body part extending into adjacent rib notches, the lower flange of a succeeding member overlapping the outer side of the upper portion of a preceding member, and welding securing adjacent members together and to said ribs.

4. A welded sheet metal boat comprising ribs formed with outer stepped edges, said ribs having upwardly extending notches between alternate steps, plating members engaging the stepped edges of said ribs and the upper edges of said plating members engaging in said notches, each member being formed of a plurality of stepped portions, the lower stepped portion of each member being formed with an inwardly projecting flange engageable against the outer side of the upper portion of a preceding member, and welding securing said members together and to said ribs.

5. In a sheet metal boat construction, an improved rib comprising an elongated bowed metal strip, the outer edge of said strip being formed with steps, and said rib also having an upwardly extending plating locking notch between each step, each notch being co-planar with the outer side of a step and forming a continuation of the upper portion of a step.

6. A sheet metal boat comprising ribs formed with outer stepped edges and a notch between each step, each notch being coplanar with and forming a continuation and extension of a step, a plurality of overlapping plating members, each member being formed of a body part and an inwardly projecting flange extending from one lengthwise edge of said body part, the opposite lengthwise edge of said body part extending into adjacent rib notches, the flange of one member overlapping the outer side of an adjacent member spaced from the lengthwise edge of that portion of said adjacent member engaging in said rib notches, and means securing adjacent members together and to said ribs.

7. A sheet metal boat construction comprising a frame formed of longitudinally bowed metal strips, and a plating secured to said strips, said plating comprising elongated metal plates formed with a flange on one edge thereof, said flange overlapping the outer flat side of a preceding plate spaced from the adjacent edge of the latter, welding securing said flange to said plate, and welding securing said plates to said strips.

JOHN F. MERCER.
